DESIGN FOR A HOSTESS CART

John C. Gridley, Alhambra, Calif.

Application April 12, 1937, Serial No. 68,713

Term of patent 7 years

To all whom it may concern:

Be it known that I, John C. Gridley, a citizen of the United States, residing at Alhambra, in the county of Los Angeles, State of California, have invented a new, original, and ornamental Design for a Hostess Cart, of which the following is a specification, reference being had to the accompanying drawing, forming part thereof.

Figure 2 is a side and front perspective view of the same, showing the serving tray in the top and the radio at the front end of the body.

I claim:

The ornamental design for a hostess cart, substantially as shown and described.

JOHN C. GRIDLEY.
